VERTICAL ROLLING MILL

Edward T. Peterson, Reading, Pa., assignor to Birdsboro Steel Foundry and Machine Company, Birdsboro, Pa., a corporation of Pennsylvania

Application November 19, 1949, Serial No. 128,377

4 Claims. (Cl. 80—56)

The present invention relates to vertical rolling mills, and especially to those which are employed in train alternatively with horizontal rolling mills.

A purpose of the invention is to provide direct motor drive on vertical shafts carrying the rolling mill rolls, the motors being located respectively one above and one below the corresponding rolls.

A further purpose is to mount the shaft and motor above one of the rolls stationary with respect to translation in the main frame.

A further purpose is to provide relative vertical and horizontal adjustment between units of a vertical rolling mill, each unit consisting of one of the rolls and a directly-connected vertical shaft and motor.

A further purpose is to mount the vertical shaft of one roll and the motor thereof below the same in a housing and to make the housing vertically adjustable and/or horizontally adjustable with respect to the other roll.

A further purpose is to provide wings at the opposite sides of the housing, to guide the wings for horizontal adjustment, preferably over horizontal surfaces of wedges, and to provide adjustment of the position of the housing by sliding the wings along the guides.

A further purpose is to provide wedge adjustment beneath the wings and preferably to coordinate the adjustment of the wedges at both sides.

A further purpose is to place hold-down wedges above the wings and to adjust the hold-down wedges to lock the wings in adjusted position for any position of the main adjustment wedges.

A further purpose is to adjust the main frame horizontally on guides, while at the same time adjusting the housing with respect to the main frame both horizontally and vertically.

A further purpose is to provide a horizontally adjustable carriage having a vertically adjustable top carriage for engaging and supporting that roll supported at the lower end of its shaft.

A further purpose is to provide a fork on the top carriage to receive the roll.

Further purposes appear in the specification and in the claims.

In the drawings I have chosen to illustrate one only of the numerous embodiments in which my invention may appear, selecting the form shown from the stand points of convenience in illustration, satisfactory operation and clear demonstration of the principles involved.

Figure 1 is a side elevation, partly in half section, of a vertical rolling mill embodying the principles of the invention.

Figure 2 is a section of Figure 1 on the line 2—2, omitting the carriage for clarity.

Figure 3 is a fragmentary enlarged section of Figure 1 on the line 3—3.

Figure 4 is a fragmentary enlarged section of Figure 3 on the line 4—4.

Figure 5 is an enlarged fragmentary plan of the carriage and fork mechanism.

Figure 6 is a side elevation of Figure 5.

Figure 7 is a section of Figure 6 on the line 7—7.

Figure 8 is a fragmentary section of Figure 6 on the line 8—8.

Describing in illustration, but not in limitation, and referring to the drawings:

It is common practice in rolling steel to vary the di-

2

rection of the major axis of the cross section of the stock, rolling for example from an oval section at one roll-stand to a circular section at the next roll-stand and then to an oval section at the succeeding roll-stand, or rolling from a diamond section at one roll-stand to a square section at the next roll-stand, to an oval section at the next roll-stand and to a circular section at the next roll-stand.

In rolling plain carbon steel or other comparatively soft stock, continuous rolling can be achieved on horizontal mills by inserting devices known as "twisters" between individual roll stands which will, at proper points, turn the stock on its own axis through about 90° before it enters the next roll-stand. In stainless steels and high alloy steels the ductility at hot working temperature is not sufficient to make the employment of twisters good practice, and personnel has been provided between each individual roll-stand to grip and twist the forward end of the stock before feeding it into the next pass.

To avoid this procedure, alternate roll stands have been provided which are horizontal in one set and vertical in the next set, thus avoiding the necessity of twisting between passes. The present invention is concerned particularly with vertical roll stands which are especially suited for use in such rolling mills, although it may be employed wherever vertical mills are used.

In the prior art, the vertical roll stands employed have been very complex, driving from remote motors through horizontal or inclined shafts and bevel gears, with provision of splines or other special means for adjustment. In accordance with the present invention the construction of the vertical roll stand is greatly simplified, eliminating the necessity for complex driving gearing, and permitting direct connection between the motors and the rolls.

In accordance with the present invention each of the rolls is directly connected to its shaft and each shaft is directly connected to its motor, one of the shafts extending above the roll to its motor located above, and the other shaft extending below its roll to its motor located below. Thus no gearing is required between either motor and its roll.

The rolls on the other hand are made both horizontally and vertically relatively adjustable, and the entire assembly is also made horizontally adjustable.

The horizontal and vertical adjustment of one roll with respect to the other is preferably accomplished by mounting the adjustable roll, its shaft and its motor in a housing, and guiding the housing for horizontal motion, and mounting it for vertical adjustment. The housing is preferably provided at both sides with wings which are horizontally guided, preferably on the horizontal surfaces of wedges, and are vertically adjusted by main wedges, and held in adjusted position by hold-down wedges.

Removal of the roll positioned at the bottom of its shaft is facilitated by a carriage movable horizontally on a track and having a top carriage movable vertically and also preferably having a fork extending horizontally on the top carriage.

The vertical roll stand, in accordance with the present invention, is supported from a foundation 20 by a horizontally extending bed 21 having parts spaced on either side of a well 22 into which depending portions of the mechanism can extend. The bed 21 has horizontally extending rails or guides 23 (best seen in Figure 1) on which rest cooperating shoes and horizontal adjustment surfaces 24 of a main frame 25. Underneath the rails 23 a shoulder 26 is engaged by a hold-down strip 27 on the frame to prevent unintended separation of the main frame from the rails.

The main frame 25 has an upright 28 and a vertically recessed forward extension 30. The forward extension 30 provides a nut 31 (Figure 2) which cooperates with an adjustment screw 32 having bearing support at 33 on the bed and provided with packing 34. It will be evident that by turning the adjustment screw 32 the entire frame, and the rolls, shafts, and motors to be later described, supported thereon, is moved horizontally back and forth

for the purpose of aligning the roll-stand with the adjoining roll stands of the mill.

The roll-stand comprises two cooperating rolls 35 and 36 on vertical axes and having any suitable grooving (not shown) as desired. The roll 35 is keyed or otherwise rigidly secured on the lower end of a vertical shaft 37 rotatably mounted in a stationary portion 38 of the main frame, and having bearing support at 40 near the bottom and at 41 near the top. Suitably keyed or otherwise secured on the shaft is a fly wheel 42 in a fly wheel housing 43, and above the fly wheel also directly connected to the shaft 37 is an electric motor 44. It will be evident that the roll 35, the shaft 37 and the motor 44 turn in bearings mounted in the main frame, but as far as translation is concerned these parts are stationary with respect to the main frame.

The recessed front extension 30 of the main frame carries a housing 45 which is movable in the main frame. In the housing 45 a vertical shaft 46, rotatably supported by bearings 47 near the top and by bearings 48 lower down, carries the roll 36 at the upper end. Below the bearing 48 a fly wheel 50 in a housing 51 is keyed or otherwise secured to the shaft. Below and depending from the fly wheel housing 51 is located an electric motor 52 directly connected to the shaft 46. Thus it will be evident that the rolling mill roll 36, the shaft 46 and the motor 52 are stationary with respect to the housing as far as translation is concerned but rotate in the bearings 47 and 48 in the housing.

At the two sides the housing is provided with straight horizontal wings 53, best seen in Figures 1 and 3. The two sides are opposite counter parts. The main frame at each side has a longitudinally and horizontally extending bench 54 below each wing, to which bench is rigidly secured (as by welding) a stationary wedge 55, thus providing effectively a wedged upper surface of the main frame above the bench. Between each wing 53 and each stationary wedge 55 is a main adjustment wedge 56 having an inclined lower surface 57 cooperating with the stationary wedge and a horizontal longitudinally extending upper guide surface 58 which provides a horizontal upwardly extending guide face for the wing immediately above.

The main adjustment wedges 56 at the opposite sides of the machine are threadedly connected at their outer ends with adjustment screws 60, which are inclined and have axes parallel to the wedge faces 57. The screws 60 carry worm wheels 61 suitably keyed or otherwise fastened on each screw. The worm wheels intergear with worms 62 on a transverse adjustment shaft 63 (Figure 4) rotatably supported at the ends in bearings 64 and having adjustment nuts 65 at the ends for wrench engagement. Thus on rotation of the adjustment shaft both screws 60 can be adjusted in unison. The screws 60 are provided with packing 66 and mounted on bearings 67 (Figure 3). Adjustment nuts 68 for wrench contact are provided at the ends of the screws.

Above each wing 53 is a stationary wedge keeper 70 secured to the main frame, extending longitudinally, and having guiding engagement with the housing at the top at 71. Between the stationary wedge keeper 70 at each side and the corresponding wing 53 is a movable hold down wedge 72 having a horizontal bottom face 73 and a wedge upper face 74 engaging the stationary wedge keeper 70. Each movable hold down wedge 72 makes threaded connection with a hold down adjustment screw 75 which is rotatably supported in a bearing 76, which is provided with packing 77 and which carries at its outer end an adjustment nut 78 for engagement by a wrench. The screws 75 are on an axis parallel to the wedge faces 74.

It will be evident that when the adjustment screws 60 are tightened they exert longitudinal pressure against their bearings to force the main adjustment wedges away from the outer end of the main frame extension 30, and likewise when the hold down adjustment screws 75 are tightened they exert pressure against their bearing 76 to force the movable hold down wedges away from the outer end of the main frame extension 30.

When the hold down wedges are loosened, the housing can be adjusted longitudinally over the guide upper surfaces 58 of the main adjustment wedges. For this purpose an adjustment screw 80 is threadedly secured in a nut 81 in the main frame extension 30, and rotatably sockets at 82 in the housing, to hold the end of the screw

in the housing. An adjustment nut 83 is provided at the outer end on the screw 80.

For the purpose of changing the roll 35, which as located in the roll stand is inaccessible to the crane above the operating floor, a bottom carriage 84 is provided, operating in a recess 85 formed at the back of the main frame in line with the roll 35. The bottom carriage 84 has wheels 36 (Figures 5, 6 and 8) which engage in suitably channel-shaped horizontally extending tracks 37 at the bottom of the recess 85. The flanges of the track channels face toward one another as shown. The bottom carriage 84 mounts a suitably pneumatic cylinder and piston 88 on a vertical axis, and the piston carries at its upper end a top carriage 90 which is suitably guided for vertical motion by extensions 91 operating in guides 92 (Figure 7) on the bottom carriage. The top carriage 90 carries a horizontal beam 93 which is secured thereto at 94, and the beam is provided with a bifurcated semi-circular forward end 95 which in its inner position engages immediately below the roll 35, taking the weight of the roll and permitting the roll to be lowered until it has been removed from the shaft 37, by lowering the piston. The carriage can then be moved bodily on the track until the hook of the crane can be brought in contact with the roll.

In operation it will be understood that once the roll-stand is assembled, it will initially be aligned with the adjoining roll-stands by moving the adjustment screw 32 in the desired direction.

For correct adjustment of the rolling surfaces on the cooperating rolls (there may be several different surfaces for use at different times, or the surfaces may require adjustment with wear), the procedure is first to loosen up on both hold-down wedges by loosening the adjustment screws 75. Horizontal adjustment in either direction can then be made by moving the adjustment screw 30. If desired, vertical adjustment can be made by moving the adjustment screws 60, moving the main adjustment wedges in either direction as required. The structure is made rigid again once the housing has assumed the correct position by tightening the hold-down wedges by tightening adjustment screws 75.

The hold-down wedges are tightened individually and therefore they can be made tight notwithstanding wear.

In operation of the bottom carriage, the bottom carriage is moved inwardly to a position in which the fork is immediately below the roll 35 and the bottom carriage cylinder energized by compressed air or other fluid until the fork supports the roll. The nut or other securing means at the bottom of the shaft 37 is removed and the roll lowered by releasing pressure from the cylinder so that the fork and top carriage can lower sufficiently to clear the lower end of the shaft 37. The bottom carriage is then pulled out to the right in Figure 2 until the roll 35 can be picked up by the hook of the crane. The roll 36 is removed directly by engagement by the crane.

It will be evident that according to the invention the mechanism is made much more simple and compact than the prior art by directly connecting each roll, shaft and motor together and by adjusting one roll, shaft and motor vertically and horizontally relative to the other.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a vertical rolling mill, cooperating first and second rolls on vertical axes, a first shaft extending vertically and rotatably supporting the first roll at its lower end, a main frame, bearings in the main frame rotatably supporting the first shaft stationarily in regards to translation with respect to the main frame, a first motor directly connected with said first shaft, rigidly connected to the main frame and positioned above the first roll on the first shaft, a second shaft extending vertically and rotatably supporting the second roll at its upper end, a housing having horizontal wings on opposite sides, bearings in the housing rotatably supporting the second shaft, a second motor directly connected with said second shaft and mounted in the housing below the second roll on the

second shaft, horizontal guides under the wings, and a screw adjustment extending between the main frame and the housing and acting to move the housing, the second shaft, the second motor and the second roll horizontally along the guides.

2. In a vertical rolling mill, cooperating first and second rolls on vertical axes, a first shaft extending vertically and rotatably supporting the first roll at its lower end, a main frame, bearings in the main frame rotatably supporting the first shaft stationarily in regards to translation with respect to the main frame, a first motor directly connected with said first shaft, rigidly connected to the main frame and positioned above the first roll on the first shaft, a second shaft extending vertically and rotatably supporting the second roll at its upper end, a housing having horizontal wings on opposite sides, bearings in the housing rotatably supporting the second shaft, a second motor directly connected with said second shaft and mounted in the housing below the second roll on the second shaft, relatively movable and stationary wedges beneath the wings at each side and adjustment means for moving the wedges horizontally and thereby moving the housing, second shaft, second motor and second roll vertically.

3. In a vertical rolling mill, cooperating first and second rolls on vertical axes, a first shaft extending vertically and rotatably supporting the first roll at its lower end, a main frame, bearings in the main frame rotatably supporting the first shaft stationarily in regards to translation with respect to the main frame, a first motor directly connected with said first shaft, rigidly connected to the main frame and positioned above the first roll on the first shaft, a second shaft extending vertically and rotatably supporting the second roll at its upper end, a housing having horizontal wings on opposite sides, bearings in the housing rotatably supporting the second shaft, a second motor directly connected with said second shaft and mounted in the housing below the second roll on the second shaft, wedge keepers extending above the wings in spaced relation and secured to the main frame, hold-down wedges extending above the wings and below the wedge keepers, screw adjustments extending from the main frame to the hold-down wedges for adjusting the same, cooperating pairs of stationary and movable wedges beneath the wings, one wedge of each pair being supported on the main frame, and screw adjustments extending from the main frame to the movable wedges.

4. In a vertical rolling mill, cooperating first and second rolls on vertical axes, a first shaft extending vertically and rotatably supporting the first roll at its lower end, a main frame, bearings in the main frame rotatably supporting the first shaft stationarily in regards to translation with respect to the main frame, a first motor directly connected with said first shaft, rigidly mounted on the main frame and positioned above the first roll on the first shaft, a second shaft extending vertically and rotatably supporting the second roll at its upper end, a housing having horizontal wings on opposite sides, bearings in the housing rotatably supporting the second shaft, a second motor directly connected with said second shaft and mounted in the housing below the second roll on the second shaft, stationary wedges on the main frame extending longitudinally in spaced relation beneath the wings, movable wedges between the stationary wedges and the wings and having horizontal surfaces engaging the bottoms of the wings, adjustments extending from the main frame to the movable wedges, keeper wedges extending longitudinally of the wings on the main frame above the wings and in spaced relation thereto, hold-down wedges extending longitudinally of the wings between the keeper wedges and the wings and having horizontal lower surfaces, vertical adjustments extending from the main frame to the hold-down wedges and horizontal adjustments extending from the main frame to the housing to shift the housing and the second shaft, second motor and second roll carried thereby horizontally along the main movable wedges.
